UNITED STATES PATENT OFFICE.

FREDERICK WM. WAGGETT, OF FOREST GATE, ENGLAND.

METAL PIANOFORTE ACTION.

1,411,820.

Specification of Letters Patent.

Patented Apr. 4, 1922.

Application filed November 29, 1919. Serial No. 341,435.

To all whom it may concern:

Be it known that I, FREDERICK WILLIAM WAGGETT, a subject of His Majesty the King of England, and resident of Forest Gate, in the county of Essex, Kingdom of England, have invented certain new and useful Improvements in Metal Pianoforte Actions, of which the following is a specification.

This invention relates to pianoforte actions made of metal and bent to shape by press tools, cast or otherwise shaped or formed, and has for its object to so improve the construction and arrangement of certain of the parts of such actions that an increased leverage is provided for the operation of the hammer-butts by the jacks, the production of noise when the jacks return to their normal position is prevented, the warping of wood and other disadvantages of wood actions are eliminated, and the manufacture of the action is more easy and economical.

The invention will now be described with reference to the accompanying drawings, in which:—

Figure 1 is a side perspective view of the improved form of hammer-butt,

Figure 2 shows in plan a portion of the metal strip or blank from which the parts of Figure 1 are formed;

Figure 3 is a side elevation of the improved combined set-off and jack-stop;

Figure 4 shows in plan a metal strip or blank used in forming the device shown in Figure 3;

Figure 5 shows two views of an adjustable cord lug for the set-off of Figure 3;

Figure 6 shows two views illustrating the improved bridle-wire and jack; and

Figure 7 shows two views of a device for securing a wooden hammer shaft to a metal hammer-butt.

Figure 8 is a vertical sectional view, partly in elevation, of a portion of a pianoforte action constructed in accordance with my invention.

Figure 9 is a front view of the parts shown in Fig. 8.

In carrying out the invention the parts of the action are formed from metal which is bent, moulded, stamped, pressed, or otherwise suitably treated to produce said parts. In Figure 1 is shown the improved hammer-butt formed from a flat strip of metal, a portion of which is shown in Figure 2, which is bent to form a triangular portion the

apex 8 of which forms the releasing point 9 for the "jack." At 10 is shown a piece of the metal cut and bent down to form a support for a piece of felt or other soft material 11 which is inserted in the hole left by the cutting of the piece 10 and may be secured to the latter by pinning, tying, sewing or otherwise, for which purpose a hole or holes may be made in the piece 10. As an alternative a piece of metal may be made to correspond with the lower side of the triangular portion and be bent to form the front apex 8 of the same and be attached to the main hammer section 12 by means of rivets or the like. The object of these constructions of the hammer-butt is to position the point 9 where the "jack" acts upon the hammer-butt at an increased distance from the hinge centre 13 and thereby gain in leverage, and to insert or attach thereto a piece of felt or other soft material to avoid noise when the jack returns to its normal position.

Figure 3 shows a combined "set-off" and jack stop one of which is used for each note instead of the ordinary set-off and jack stop, and is attached to the action-rail by means of one or more screws or otherwise suitably. The strip of metal 14 shown in Figure 4 is bent to the shape shown in Figure 3 the portion 15 being preferably spooned or hollowed such as indicated to prevent friction as it actuates the jack 16 for the purpose of setting it off. The eyed screw 17 adjusts the set-off and passes through a clearance hole 18 made at the upper end of the main set-off and screws into a threaded hole 19 provided at the lower end. The lower end of the set-off is preferably made narrow for a greater length than the upper end, thereby facilitating the raising or releasing of the lower end as the screw 17 is turned.

A lug 20 formed on the strip 14 is provided with a hole in the centre which preferably has a slot or channel leading into it as shown at 21. A cord is threaded from end to end of the action, or certain parts thereof, passing through each set-off and adjustably attached for tension to the action standards or rail. This cord takes the place of the usual jack-stop. The channel or slot 21 enables the cord to be pressed or forced sideways into the hole instead of being threaded therethrough. As the jack which is shown by dotted lines in Figure 3 is disengaged from the hammer-

butt when set-off it will be prevented from moving too far from its usual position by the said cord, the position of the lug 20 and of the cord being such that the jack 5 can only be set off to a given extent and therefore easily drops back to its normal position immediately the releasing or partial releasing of the key permits, thus preventing "blocking". The lug may be adjustably fitted to the main set-off. For instance, as shown in Figure 5, the lug 20^a 10 may be formed on a sleeve 22 adapted to slide upon the set-off and to be fixed in position thereon by a set screw or otherwise suitably. To avoid noise in working the aforesaid cord may be covered with felt or have washers of felt or similar material 15 threaded thereon.

Figure 6 appertains to an improved 20 method of fixing the looped tape or cord to the "bridle-wire" 23 which is accomplished by means of a slot and hole on each side of the wire at 24. The loop of the cord or tape is put over the wire and pressed 25 or forced sideways into the holes through the slots; by inverse method it can also be removed. The bridle-wire 23 is shown cut from the centre of a metal strip which also forms the "check" 25, the upper part of 30 the bridle-wire being made larger to allow for the holes and also to allow room for the tape or cord to pass freely to the balanced hammer.

Figure 7 shows a clip or fastening by 35 means of which a wood hammer-shank can be fastened to a metal hammer-butt. The clip may be made of metal tube and may be cut away in the middle as shown at 26 to give greater holding power on the wood 40 shank, or it can be made by metal stamping and bent round, the joint being brazed or otherwise fixed or over-lapping and held by the screw 27 passing through both ends, or the clip may be cast. The clip is passed 45 over the U-shaped portion 12^a of the hammer-butt, the screw 27 acting against the same. After the wood-hammer shank has been placed in position within the U-shaped portion 12^a of the hammer-butt the screw 50 27 will draw the clip firmly to the wood thereby holding the hammer in place. The clip being of round section, and of such a size that the hammer-shank fits within it, enables the hammer to be fixed slanting to 55 one side or "cast" over by cutting away the wood in a slanting direction on one side in the same manner as in fitting the hammer-shank into the hole in the hammer-butt of a wood action.

60 What I claim is:—

1. A pianoforte action comprising a hammer-butt made of metal and having a forwardly extending portion to provide a point disposed a considerable distance in front of 65 the hinge of the butt and against which

point the jack acts, thus increasing the leverage, and a combined metal set off and jack-stop for each section or note of the action.

2. A pianoforte action comprising a hammer-butt made of metal and having a forwardly extending portion to provide a point disposed a considerable distance in front of the hinge of the butt and against which point the jack acts, thus increasing the leverage, 75 and a combined adjustable metal set-off and jack-stop for each section or note of the action.

3. A pianoforte action comprising a hammer-butt made of metal and having a forwardly extending portion to provide a point disposed a considerable distance in front of the hinge of the butt and against which point the jack acts, thus increasing the leverage, 80 and a combined adjustable metal set-off and jack-stop for each section or note of the action and consisting of a strip of metal which is bent to U-shape, has one of its arms shaped to actuate and set-off the jack, and has its two arms adjustable relatively to one 85 another by means of an adjusting screw.

4. A pianoforte action comprising a hammer-butt made of metal and having a forwardly extending portion to provide a point disposed a considerable distance in front of the hinge of the butt and against which point the jack acts, thus increasing the leverage, a combined metal set-off and jack-stop for each 95 section or note of the action, and a perforated lug on said set-off for holding a check, 100 or guard in position.

5. A pianoforte action comprising a hammer-butt made of metal and having a forwardly extending portion to provide a point disposed a considerable distance in front of the hinge of the butt and against which point the jack acts, thus increasing the leverage, combined metal set-offs and jack-stops one for each section or note of the action, 105 perforated lugs on said set-offs and a 110 cord passing through the series of lugs.

6. A pianoforte action comprising a hammer-butt made of metal and having a forwardly extending portion to provide a point disposed a considerable distance in front of the hinge of the butt and against which point the jack acts, thus increasing the leverage, a combined metal set-off and jack-stop for each section or note of the action, 115 and a bridle-wire which is perforated and slotted on both sides for the attachment thereto of a looped tape or cord.

7. A pianoforte action comprising hammer-butts each made of metal and having a forwardly extending portion to provide a point disposed a considerable distance in front of the hinge of the butt and against which point the jack acts, thus increasing the leverage, a combined metal set-off and jack-stop for each section or note of the ac- 125 130

tion, and bridle-wires each of which is perforated and slotted on both sides for the attachment thereto of a looped tape or cord and is formed integrally with a jack or check.

8. A pianoforte action comprising hammer-butts each made of metal and having a forwardly extending portion to provide a point disposed a considerable distance in front of the hinge of the butt and against

5 which point the jack acts, thus increasing

the leverage, a combined metal set-off and jack-stop for each section or note of the action, bridle-wires each of which is perforated and slotted on both sides for the attachment thereto of a looped tape or cord, and a tubular metal clip by means of which a wood hammer-shank is fastened to the metal hammer-butts.

10 In testimony whereof I have hereunto signed my name.

FREDERICK WM. WAGGETT.
